DESIGN FOR A COMBINED CAN PUNCH AND DISPENSER

Frances Lucy Chamberlain, Sinclairville, N. Y.

Application November 8, 1939, Serial No. 88,128

Term of patent 3½ years

To all whom it may concern:

Be it known that I, Frances Lucy Chamberlain, a citizen of the United States, residing at Sinclairville, in the county of Chautauqua and State of New York, have invented a new, original, and ornamental Design for a Combined Can Punch and Dispenser, of which the following is a specification, reference being had to the accompanying drawing, forming part thereof.

I claim:

The ornamental design for a combined can punch and dispenser, as shown.

FRANCES LUCY CHAMBERLAIN.
